UNITED STATES PATENT OFFICE

2,384,488

SHOE SEWING MACHINE AND THREAD
CONTROLLING DEVICE

Thomas F. Orr, St. Louis, Mo., and Leonard S. Curtin, Belmont, Mass., assignors to United Shoe Machinery Corporation, Flemington, N. J., a corporation of New Jersey

Application August 20, 1943, Serial No. 499,364

5 Claims. (Cl. 112—59)

The present invention relates to high-speed shoe sewing machines and as herein illustrated is embodied in an improved thread-controlling and tension device for an eye-pointed needle sewing machine of the wax-thread type similar to that disclosed in United States Letters Patent No. 1,864,510, granted June 21, 1932, upon an application filed in the name of Bernard T. Leveque, and in United States Letters Patent No. 2,355,107, granted August 8, 1944, upon an application pending with the present application and filed in the names of Edward Quinn and Leonard S. Curtin.

The machine of the Leveque patent is provided with a treadle-controlled driving and stopping mechanism for disconnecting the needle from the main sewing shaft when the needle is disengaged from the work in the final sewing cycle of a seam. The disconnection may occur while the machine is running at relatively high speeds so that the parts for disconnecting the needle are given an extremely quick motion. A thread cutter also is provided in the machine and actuated by the driving and stopping mechanism as the needle is being disconnected from the sewing shaft to sever the thread extending from the final stitch in a seam close to the eye of the needle. To avoid pulling the end of the thread from the needle eye or from the work when starting a new seam, a slack-thread pull-off is employed in the patented machine, acting between a thread-waxing pot and a stationary dry-thread tension device located at the supply side of the wax pot. Such an arrangement is entirely satisfactory when good quality linen thread is available. When low quality short-fiber cotton thread is utilized for sewing, the ends of the dry fibers become broken off and wedged between the members of the tension device, resulting in improper sewing operations. To avoid this difficulty a wet-thread tension device located between the wax pot and the work is required, the wax on the thread holding the fibers in place while moving over the wet-thread tension device.

As explained in the Quinn and Curtin patent above identified, the usual form of wet-thread tension device consists of a brake-retarded rotating wheel the periphery of which is provided with thread-engaging tabs for securing the thread wound thereon against substantial slippage in spite of the lubricating qualities of unsolidified wax on the thread.

In order to avoid withdrawing the end of the thread from the eye of the needle or from the work while the pull-off device is acting in the machine of the Leveque patent, a one-way thread

clamping lock is mounted between the pull-off device and the wax pot. Due to the relatively rapid movement which may be imparted to the pull-off device by the driving and stopping mechanism while disconnecting the needle and to the ineffectiveness of a one-way clamping lock on thread to which wax has been applied, it is impractical to employ such a lock between the wet-thread tension wheel and the needle in the machine of the Quinn and Curtin patent. Furthermore, if slack thread is provided by rotating the tension wheel in that machine before starting a new seam, some form of ratchet must be employed which preferably is of inexpensive and simple construction. With the use of a ratchet for rotating the tension wheel, the force of reaction exerted by the ratchet on the wheel while the ratchet is being reset for a new operation may cause the wheel to take up thread sufficient in amount to offset the length provided at the beginning of a seam or to withdraw the thread from the needle eye.

The present invention, therefore, has for an object the provision of a simplified and improved construction and arrangement of parts for providing a slack length of sewing thread sufficient in amount to avoid withdrawing the end of thread from the eye of the needle or from the work at the beginning of a seam inserted by a high-speed machine of the type referred to without the use of a separate thread clamping lock or of other means separate from the tension device, the operation of which would be adversely effected by the presence of wax on the thread. More generally, the invention is intended to simplify the construction and improve the manner of operation in an eye-pointed needle sewing machine having a driving and stopping mechanism for disconnecting the needle from the sewing shaft, a wet-thread tension device, and a thread cutter acting to sever the thread close to the eye of the needle at the end of a seam.

In the attainment of these and other objects, the present invention is embodied in a high-speed eye-pointed needle shoe sewing machine having a driving and stopping mechanism acting to disconnect the needle from the main sewing shaft of the machine with the needle in a position disengaged from the work, a thread cutter actuated automatically at the end of a seam to sever the thread close to the eye of the needle after the needle is disconnected from the sewing shaft, a rotary thread tension wheel, and ratchet means to be actuated by the driving and stopping mechanism when starting the machine in operation to

provide slack thread by rotation of the tension wheel and to be reset thereafter by the driving and stopping mechanism before the thread cutter is actuated at the end of a seam. By resetting the tension-wheel rotating means before the thread cutter is actuated, there is no possibility of withdrawing the severed end of the thread from the eye of the needle, so that the force of reaction on the tension wheel while the tension-wheel rotating means is being reset cannot cause the wheel to be rotated in a direction to take up thread and accordingly no special thread clamping lock or other moving parts are required. Where the tension-wheel rotating means comprises a pawl and ratchet member for rotating the tension wheel according to this feature of the invention, the pawl and ratchet member move together to rotate the tension wheel in a direction to provide thread, and the pawl moves over the ratchet member idly while being reset before the thread cutter acts at the end of a seam.

Other features of the invention consist in a novel and improved thread-controlling and tension device of general utility and in certain constructions, combinations and arrangements of parts hereinafter described and claimed, the advantages of which will be apparent to those skilled in the art from the following description.

In the accompanying drawings,

Fig. 1 is a view in side elevation, looking from the right, of the forward portion of a shoe sewing and lasting machine, partly broken away, embodying the features of the present invention;

Fig. 2 is a view in left side elevation of the upper forward portion of the machine illustrated in Fig. 1;

Fig. 3 is a sectional detail view, on an enlarged scale, taken along the line III—III in Fig. 2, of the thread-controlling and tension device;

Fig. 4 is a detail view, taken in section along the line IV—IV in Fig. 3, of the tension wheel and the pull-off pawl and ratchet of the tension device;

Fig. 5 is a detail view, on a still further enlarged scale, of the pawl illustrated in Fig. 4;

Fig. 6 is a further detail plan view of both the pawl and ratchet.

The illustrated machine is a combined sewing and lasting machine and, so far as its stitch-forming and lasting devices are concerned, is the same in construction and mode of operation as the machine disclosed in the patent to Leveque above referred to. The lasting operations are performed in part by a pair of work-gripping and feeding rolls 2 between which the upper and sole of a shoe are drawn into lasted relationship. For controlling the sewing operations and at the same time enabling the machine to be stopped abruptly while sewing at high speeds, the machine is provided with a driving and stopping mechanism for disconnecting the stitch-forming devices from their actuating mechanism. The tension device except as hereinafter described is the same as that of the corresponding device of the Quinn and Curtin patent.

The illustrated tension device, as in the machine of the Quinn and Curtin patent, comprises a rotary thread-engaging tension wheel 4 mounted to receive one or more turns of thread while passing between a wax pot 6 and the stitch-forming devices, which include a straight eye-pointed needle 8 and a take-up 10 mounted at the upper end of a reciprocating needle bar 12. The periphery of the tension wheel is provided with

70 thread-guiding tabs of well-known construction bent alternately in opposite directions forming crevices within which the thread is passed in order to insure an effective grip on the thread and to prevent slippage in spite of the presence of liquefied wax on the thread. The tension wheel is rotatably mounted upon a shouldered shaft 14 also rotatably supported in a sleeve-like bearing 16 secured by a set screw 18 within a hub at the upper end of an arm 20. The arm 20 is clamped at its lower end to a bracket adjustably secured on the machine frame at a position which will enable the thread to pass in a desired direction toward and from the tension wheel. The brake for the tension wheel consists of friction washers 22 backed by the end of the bearing 16 at one side of the tension wheel and by a washer 24 at the other side of the tension wheel. For applying pressure to the brake, the reduced end of the shaft 14 has coiled about it two springs, one 26 inside the other 28, wound in opposite directions and of relatively different strengths. The outer spring 28 which is the weaker is compressed between the washer 24 and a thumb nut 30 threaded on the reduced end of the shaft 14. The outer spring exerts a slight tension on the thread at all times. The inner spring 26 is compressed between the thumb nut 30 and a collar 32 held, when the machine is stopped, against a shoulder 34 on the shaft 14 and, when the machine is running, against the brake washer 24.

To enable the inner brake spring 26 to be rendered ineffective, the tension wheel shaft 14 is moved endwise and is threadedly received in the hub of a controlling arm 36, a check nut 38 being provided to lock the shaft to the arm. One face of the hub on the arm is formed with a cam 40 cooperating with a projection 42 at one end of the sleeve bearing 16 so that, when the arm 36 is rocked in one direction, the cam will move away from the projection 42 causing the spring 28 to draw the shaft 14 endwise until the shoulder 34 engages the collar 32 and moves it away from the washer 24. When the shoulder 34 engages the collar 32, expansion of the spring 26 is stopped and the pressure of the spring 26 on the tension wheel brake is relieved. Thus, the force of the stronger tension spring 26 is rendered ineffective, the weaker spring 28 only acting on the brake. The purpose of the weaker spring 28 is to prevent excessive stripping of thread from the machine when the machine is stopped. When the arm 36 is moved in the opposite direction, the cam 40 will climb up the projection 42 compressing the spring 28 slightly and bringing the collar 32 to bear against the washer 24. The heavy tension spring 26 is thus rendered effective to act on the tension wheel brake and to impart a sewing tension to the thread.

60 In stopping the machine of the Quinn and Curtin patent and of the Leveque patent at the end of a seam, the thread is automatically severed by a thread cutter 27 close to the eye of the needle and, unless a length of thread is provided so as to become slack at the eye of the needle, when the machine is started in a new sewing operation, the severed end of the thread may become withdrawn from the needle eye. The operator thus must give special attention to the amount of slack thread available or a new threading operation may be found necessary.

To avoid the difficulty of frequently rethreading the machine of the present invention and to provide slack thread at the needle sufficient in length for the proper formation of the first stitch

in a seam, the tension wheel 4 has secured to one side a dished washer 44 the flanged edge of which is formed with a series of ratchet teeth engaged by a pawl 46. The pawl 46 is constructed of relatively thin resilient sheet metal having a 5 disk-shaped portion integrally attached thereto. The disk portion of the pawl is perforated to receive the tension wheel shaft 14 and is made fast to the washer 44 so that, when the washer is rotated, it will impart a corresponding movement 10 to the pawl. To rotate the pawl, the washer 44 and the disk portion of the pawl are formed with aligned slots within which is fitted a key 48 slidably mounted in a suitable keyway in the shaft 14. When the shaft, which has secured to it the 15 arm 36, is rotated with the arm, corresponding movement is imparted to the pawl in addition to the lengthwise movement of the shaft. The pawl and ratchet washer are so arranged that the tension wheel will be rotated to provide slack 20 thread when the machine is started in operation on a new seam.

To avoid any tendency for the tension wheel to be rotated in a reverse direction so as to unthread the needle, the connections for actuating the arm 36 in the present machine are adjusted to cause the pawl and ratchet members to be rotated relatively and to reset the pawl on the ratchet before the thread is severed at the end of a seam. In this way that portion of thread connecting the 25 work with the tension wheel prevents the wheel from being rotated in a reverse direction. The arm 36 is directly non-yieldingly connected to a control member for the driving and stopping mechanism so that a pawl resetting movement will be imparted to the arm before the driving and stopping mechanism has had an opportunity to stop the machine at the end of a seam. On the other hand, the mechanism for actuating the 30 thread cutter comprises a lost-motion connection between the thread cutter and the driving and stopping mechanism.

The connections for moving the arm 36 to actuate and reset the pawl 46 comprise an adjustable horizontal link 50 pinned at one end to the arm 36 and at the other end to a bell-crank lever 52 fulcrumed on the machine frame, a vertical link 54 being connected between the lever 52 and an arm 66 fastened to a treadle-controlled rockshaft 58 inside the machine frame. Outside the frame, the rockshaft 58 has attached to it an arm 60, and a treadle-actuated rod 62 passes loosely through an eye at the free end of the arm 60. When the treadle rod 62 is depressed, a notched arm 64 on the rockshaft 58 inside the machine frame is moved away from a sleeve on a downwardly extending arm of a needle-actuating bell crank 66, freeing the needle-actuating mechanism for reciprocation. At the same time, the bell crank 66 is connected to a continuously oscillating bell crank 68 to start the sewing operations. When the sewing operations are started, the connections between the treadle-controlled rockshaft 58 and the tension-wheel controlling arm 36 rotate the tension wheel sufficiently to provide slack thread at the eye of the needle, thus enabling proper formation of the first stitch in a seam. This movement of the arm 36 also effects a sewing tension on the thread by causing the inner sewing tension spring 26 to act on the tension-wheel, thus causing it to produce an effective sewing tension on the thread. The return movements of the parts to reset the pawl 46 thus described are effected by a coil spring 69 (see Fig. 1) surrounding the treadle rod. These

return resetting movements cause the spring 26 to become ineffective.

The mechanism for actuating the thread cutter includes an arm 70 secured to the treadle-controlled rockshaft 58, a hook 72 pivotally connected at one end to the arm 70, with its hooked end surrounding a stud 74 projecting from a rocking member 76 having a number of arms one of which is connected to the thread cutter. The hook 72 is so arranged that it causes movement of the rocking member 76 only during the ends of the movement imparted to the hook 72, the hook at other times being disengaged from the stud 74 or sufficiently displaced as to be ineffective in moving the rocking member 76. The rocking member 76 is also a part of a toggle including a downwardly extending arm of the member and a spring link 78 connecting the rocking member with a pivoted support member on which one of the work-gripping and feeding rolls 2 is rotatably mounted, the spring link connection causing the work to be gripped yieldingly by the rolls. The same arm of the rocking member 76 also is connected through a vertical link 80 to a lever 82 fulcrumed at 84 on the machine frame with an arm underlying one end of a spring-actuated lever 86 to which the thread cutter 27 is secured, these parts being the same in construction and mode of operation as in the machine of the Leveque patent. The purpose of the spring link 78 is not only to move the feeding rolls 2 together but also to lock the rocking member 76 in its actuated position either when the machine is stopped or during sewing. Accordingly, the toggle formed by the rocking member 76 and the spring link is adjusted to move past centers in one direction or the other. During sewing, the connections between the rocking member 76 hold the thread cutter out of engagement with the thread, and at the end of a seam enable the thread to be severed by the thread cutter. The connections for moving the ratchet and brake-controlling arm 36 are so adjusted that substantially all the necessary movement is imparted to the arm in either direction before the rocking member 76 of the thread cutter mechanism is shifted from its position.

During sewing, it is common practice for the operator to vary the position of the treadle-controlled rod 62 in order to control the sewing speed of the machine, the rod 62 also being connected with a clutch-controlling lever (not shown). The movement of the treadle rod 62 in this way will have no effect on the sewing inasmuch as it is insufficient in extent to impart a full-length movement to the tension wheel arm 36. Any rotation of the tension wheel by movement of the arm 36 during sewing is insufficient to produce slack thread and defective stitches since continual movement of the thread toward the needle occurs at a rate greater than any possible rotation of the tension wheel by the connections to the tension-controlling arm 36.

The nature and scope of the invention having been indicated and the machine embodying the several features having been specifically described, what is claimed is:

1. A shoe sewing machine having, in combination, stitch-forming devices including an eye-pointed needle, mechanism for actuating the stitch-forming devices, driving and stopping mechanism for disconnecting the needle from the actuating mechanism in a position with the needle disengaged from the work, a thread cutter

actuated by the driving and stopping mechanism to sever the thread at the end of a seam close to the eye of the needle after being disconnected from the actuating mechanism, a rotary tension wheel having thread-engaging means about its periphery, and ratchet means for the tension wheel actuated by the driving and stopping mechanism when starting the machine in operation to provide slack thread at the needle sufficient in length for the proper formation of the first stitch of a seam, said ratchet means being arranged to be reset before the thread cutter is actuated at the end of a seam.

2. A shoe sewing machine having, in combination, stitch-forming devices including an eye-pointed needle, mechanism for actuating the stitch-forming devices, driving and stopping mechanism for disconnecting the needle from the actuating mechanism in a position with the needle disengaged from the work, a thread cutter actuated by the driving and stopping mechanism to sever the thread at the end of a seam close to the eye of the needle after being disconnected from the actuating mechanism, a rotary tension wheel having thread-engaging means about its periphery, pawl and ratchet means for rotating the tension wheel to provide a length of slack thread sufficient for the first stitch in a seam, and connections actuated by the driving and stopping mechanism in starting the machine in operation to rotate the tension wheel in a direction to provide slack thread and to rotate one member of the pawl and ratchet means in the other direction at the end of a seam before the thread cutter is actuated in preparation for a new slack thread providing rotation of the tension wheel.

3. A shoe sewing machine having, in combination, stitch-forming devices including an eye-pointed needle, mechanism for actuating the stitch-forming devices, driving and stopping mechanism for disconnecting the needle from the actuating mechanism in a position with the needle

5 disengaged from the work, a thread cutter, a lost-motion connection between the driving and stopping mechanism and the thread cutter for actuating the thread cutter when the needle is being disconnected, pawl and ratchet means for rotating the tension wheel to provide a length of slack thread sufficient for the first stitch of a seam, and non-yieldingly attached connections between the driving and stopping mechanism and the pawl and ratchet for causing the tension wheel to be rotated in a direction to provide slack thread and in a direction to reset the pawl and ratchet for a new operation before the thread cutter is actuated at the end of the previous seam.

10 15 4. In a thread-controlling and tension device for sewing machines, the combination with a rotary thread tension wheel, a friction brake for the wheel, pawl and ratchet means for rotating the wheel to provide slack thread, mechanism for actuating and resetting the pawl and ratchet means, and means actuated by movement of the pawl and ratchet means while providing slack thread to apply the friction of the brake on the wheel and while being reset for a new slack thread-providing movement to relieve the friction of the brake on the wheel.

20 25 30 35 5. In a thread-controlling and tension device for sewing machines, the combination with a rotary thread tension wheel, a friction brake for the wheel, a pair of springs for causing the brake frictionally to engage the tension wheel, pawl and ratchet means for rotating the wheel to provide slack thread, mechanism for actuating and resetting the pawl and ratchet means, and means actuated by movement of the pawl and ratchet means while providing slack thread to render one of the springs effective and while being reset for a new slack thread-providing movement to render said spring ineffective.

actuated by the driving and stopping mechanism to sever the thread at the end of a seam close to the eye of the needle after being disconnected from the actuating mechanism, a rotary tension wheel having thread-engaging means about its periphery, and ratchet means for the tension wheel actuated by the driving and stopping mechanism when starting the machine in operation to provide slack thread at the needle sufficient in length for the proper formation of the first stitch of a seam, said ratchet means being arranged to be reset before the thread cutter is actuated at the end of a seam.

2. A shoe sewing machine having, in combination, stitch-forming devices including an eye-pointed needle, mechanism for actuating the stitch-forming devices, driving and stopping mechanism for disconnecting the needle from the actuating mechanism in a position with the needle disengaged from the work, a thread cutter actuated by the driving and stopping mechanism to sever the thread at the end of a seam close to the eye of the needle after being disconnected from the actuating mechanism, a rotary tension wheel having thread-engaging means about its periphery, pawl and ratchet means for rotating the tension wheel to provide a length of slack thread sufficient for the first stitch in a seam, and connections actuated by the driving and stopping mechanism in starting the machine in operation to rotate the tension wheel in a direction to provide slack thread and to rotate one member of the pawl and ratchet means in the other direction at the end of a seam before the thread cutter is actuated in preparation for a new slack thread providing rotation of the tension wheel.

3. A shoe sewing machine having, in combination, stitch-forming devices including an eye-pointed needle, mechanism for actuating the stitch-forming devices, driving and stopping mechanism for disconnecting the needle from the actuating mechanism in a position with the needle

5 disengaged from the work, a thread cutter, a lost-motion connection between the driving and stopping mechanism and the thread cutter for actuating the thread cutter when the needle is being disconnected, pawl and ratchet means for rotating the tension wheel to provide a length of slack thread sufficient for the first stitch of a seam, and non-yieldingly attached connections between the driving and stopping mechanism and the pawl and ratchet for causing the tension wheel to be rotated in a direction to provide slack thread and in a direction to reset the pawl and ratchet for a new operation before the thread cutter is actuated at the end of the previous seam.

10 15 4. In a thread-controlling and tension device for sewing machines, the combination with a rotary thread tension wheel, a friction brake for the wheel, pawl and ratchet means for rotating the wheel to provide slack thread, mechanism for actuating and resetting the pawl and ratchet means, and means actuated by movement of the pawl and ratchet means while providing slack thread to apply the friction of the brake on the wheel and while being reset for a new slack thread-providing movement to relieve the friction of the brake on the wheel.

20 25 30 35 5. In a thread-controlling and tension device for sewing machines, the combination with a rotary thread tension wheel, a friction brake for the wheel, a pair of springs for causing the brake frictionally to engage the tension wheel, pawl and ratchet means for rotating the wheel to provide slack thread, mechanism for actuating and resetting the pawl and ratchet means, and means actuated by movement of the pawl and ratchet means while providing slack thread to render one of the springs effective and while being reset for a new slack thread-providing movement to render said spring ineffective.
